CONVERTIBLE TABLE AND CABINET

John Fanarjian, Union City, N. J.

Application January 16, 1936, Serial No. 59,378

3 Claims. (Cl. 311—60)

This invention relates to improvements in convertible table and cabinet.

One of the objects of this invention is to produce a foldable table convertible into a relatively narrow cabinet and comprising a stationary centrally-located flat top portion forming the top of the cabinet and oppositely folding leaves forming sides thereof, said device having movable legs extensible when converted into a table, and contractible or foldable when converted into cabinet form.

Another object of my invention is, in a device of the character described, to provide extensible legs movable from contracted to extended position by the movement of the said foldable leaves.

With these and other objects in view the invention comprises the combination of members and arrangement of parts so combined as to co-operate with each other in the performance of the functions and the accomplishment of the results herein specified, and comprises in one of its adaptations the species or preferred form illustrated in the accompanying drawings, in which:—

Fig. 1 is a view in perspective of a convertible cabinet and table embodying my invention;

Fig. 2 is an end elevation of the cabinet shown in Fig. 1 with the end member removed therefrom;

Fig. 3 is a view similar to Fig. 2 with the foldable legs and adjacent members removed;

Fig. 4 is a section on the line 4—4 of Fig. 2 looking in the direction of the arrows;

Fig. 5 is an end elevation of the device shown in extended position.

Fig. 6 is a fragmentary elevation and section on the line 6—6 of Fig. 3 looking in the direction of the arrows;

Fig. 7 is a transverse section on the line 7—7 of Fig. 6, looking in the direction of the arrows;

Fig. 8 is a transverse section on the line 8—8 of Fig. 6, looking in the direction of the arrows;

Fig. 9 is a fragmentary elevation of one of the sliding elements and connections therewith, and

Fig. 10 is a section on the line 10—10 of Fig. 4 looking in the direction of the arrows.

Referring now to these drawings, 1 indicates a base member of a cabinet including a bottom member 2 spaced from an intermediate member 3 to provide a compartment for a drawer 1'. Mounted at opposite ends of the base member in any suitable manner are a pair of vertical slide frames 4, 4 each having double grooves 6 and 7. Said frames 4, 4 have top rails 4a on which, as shown, is supported the centrally disposed flat table top portion 5, thus providing an oblong

skeleton or frame to which foldable leaves 24 and legs 29 are applied in such manner that the opening or extension movement of the leaves will cause the extension movement of the legs 29 and the folding or closing movement of the leaves 24 will cause the contraction or inward movement of the legs 29.

In order to accomplish these movements the foldable leaves 24 are hinged by hinges 25 to side edges of the centrally-located table top member 5 so as to be foldable to form the sides of a cabinet when in folded position and to be extensible into registration with the centrally-located member 5 to provide an extended table top.

The foldable leaves 24 are, in the embodiment shown, connected through slides 10 and 11, movable in the frame 4 with the legs 29 in such manner that the extension movement of the leaves 24 will cause a downward and outward movement of the legs 29 and a closing movement of the leaves 24 will cause an upward and inward movement of said legs 29.

In the embodiment shown, the table leaves 24 are provided on their under surface with brackets 23 connected by links 22 with the bottom portion of a block 11 slidable in ways in the frame 4 and the said slidable block 11 is connected by the flexible connection 16, running over pulley 18, to a block 10, also slidable in ways in the frame 4 and which carries the legs 29 pivotally mounted thereon. In the embodiment shown the flexible connection 16 is connected with the block 11 through a slide member 14 which slides in way members 15, having therebetween a central channel 15' through which the member 16 extends. This connection of the slidable block 11 with the connection 16 is desirable in order to compensate for the difference in extended movement of the two blocks and in the preferred form of my invention the flexible connection is continuous and extends around the pulley 17 mounted at the lower end of the cabinet so that the two slides 10 and 11 and the flexible connection form a unitary and compensating system in which movement of one of the slides will be transmitted to the other.

As the bottom surface of the foldable leaves 24 are connected to the slide 11 it will be obvious that the opening movement of the member 24 will cause an upward movement of the slide 11 and that this upward movement of the slide 11 will cause the slide 10 which carries the legs 29 to be moved downwardly. The lower ends of these legs rest upon a wedge member 27 which is adapted during the downward movement thereof to force the same to swing upon its pivots 28 outwardly

and into the position shown in Fig. 5 in which the sides of the members 29 will abut against the wedge member 27 and the edges 29' thereof will be moved into parallel relationship to each other 5 and into contact with a stationary stop element 19' mounted on the inner surface of the wall 19 of the cabinet. Lowering of the leaves will conversely result in a downward movement of the slide 11 and an upward movement of the leg-carrying slide 10. During this upward movement 10 the upper edges of the legs 29 come in contact with an upper wedge member 26 which forces the top portions of the legs above the pivots apart and swings the body portion thereof into closed 15 or folded position.

In the preferred embodiment of my invention the slide 11 is releasably latched in its raised position to lock the leaves 24 in extended position and for this purpose I mount upon the bottom surface 20 of the member 5 a pair of latches 31 engageable with the shelf 11' on the slide 11 and connected by a pair of flexible connections 32 passing over pulleys 30 and connected to a single operating member 32' the end 33 of which may be grasped 25 by the operator to release the latch member 31 and permit a downward movement of the slide 11 with a consequent folding movement of the leaves 24.

In the preferred embodiment of my invention 30 shown, the mechanism beneath the member 5 is enclosed in a compartment 9 formed between the ends 4^a, sides 4' and bottom 4^b of a pan-shaped element connected to the frame 4.

As illustrated the inside of the cabinet is lined 35 with metal walls to provide compartments 20 and 20' preferably divided from each other by a transverse partition 20^a.

From the above it will be seen that I have provided a convertible table-cabinet device which, 40 when in extended position will be solid because of the extension of the legs and which when in folded condition will be small and compact and will be portable, a carrying handle 34 being provided for this purpose. The ends of the cabinet are closed 45 and the slides enclosed by end members 19.

If desired, the lower compartment 20 may be used to carry and contain ice, and under such circumstances I provide a drain-pipe or tube 20^b extending from the compartment 20 to the bottom 50 of the cabinet.

Having described my invention, I claim:

1. A convertible table and cabinet comprising a supporting frame, a stationary table-top member supported on said frame, foldable table-top

leaves hinged at opposite edges of said stationary member and movable into horizontally-disposed extended position and into parallel vertically-disposed folded position, said frame being provided at the ends thereof with pairs of legs shorter than the height of said frame and having a combined sliding and pivotal movement into extended and folded position, said legs in extended position projecting outwardly from said frame and in folded position being foldable within the confines 5 of said supporting frame, and mechanism connecting said foldable table-top members with said foldable legs to cause extension and folding movements of the legs automatically upon similar movements of table-top members. 10

2. A convertible table and cabinet comprising a supporting frame, a stationary table-top member supported on said frame, foldable table-top leaves hinged at opposite edges of said stationary member and movable into horizontally-disposed 20 extended position and into parallel vertically-disposed folded position, said frame being provided at the ends thereof with pairs of legs shorter than the height of said frame and having a combined sliding and pivotal movement into 25 extended and folded position, said legs in extended position projecting outwardly from said frame and in folded position being foldable within the confines of said supporting frame, and counter-movable slide mechanism having connections with said foldable legs and with said 30 table top members to cause extension and folding movements of the legs automatically upon similar movements of table-top members.

3. A convertible table and cabinet comprising 35 a supporting frame, a stationary table-top member supported on said frame, foldable table-top leaves hinged at opposite edges of said stationary member and movable into horizontally-disposed extended position and into parallel vertically-disposed folded position, two pairs of slide members supported in said frame, the members of a pair being mounted to have counter-movement relative to each other, a pair of legs pivotally mounted on one member of each of the pairs of slides and 40 movable thereby into extended and folded positions, said legs in extended position projecting outwardly from said frame and in folded position being foldable within the confines of said supporting frame, and means connected with the 45 other members of said pairs of slides for moving said legs alternately into extended and folded positions. 50

JOHN FANARJIAN.
